F. DÜRR

INTERNAL COMBUSTION ENGINE

Filed July 23, 1926

Inventor:

Fritz Dürr

Per *C. Heesen*

Attorney

UNITED STATES PATENT OFFICE.

FRITZ DÜRR, OF MUNICH, GERMANY.

INTERNAL-COMBUSTION ENGINE.

Application filed July 23, 1926, Serial No. 124,381, and in Germany July 27, 1925.

My invention relates to improvements in internal combustion engines, and more particularly to two-cycle blower engines with a uniflow scavenging system.

5 There are already known internal combustion engines, particularly two-cycle blower engines with uniflow scavenging, in which the scavenging and the charging air are controlled by means of a rotary valve.

10 My improved combustion engine of this type is distinguished from the hitherto known engines by the injecting nozzle for the supply of the liquid fuel opening axially into the tubular rotary valve and by the necessary quantity of fuel being added to the charging air in countercurrent by means of a pump operating in the cycle of the rotary valve.

15 According to a further development of my invention a cam is provided upon the rotary valve itself for the drive of the fuel pump.

20 In the drawing attached hereto one embodiment of my invention is illustrated by way of example.

25 Referring to the single figure of the drawing which illustrates a longitudinal section through my improved engine, 1 is the cylinder of the engine, and 2 the piston reciprocated therein by means of the connecting rod 3. In the cylinder head is provided a tubular rotary valve 4 which may be rotated by means of a sprocket wheel 5, for instance.

30 Into this valve provided with a scavenging slot or port 6 projects axially the fuel nozzle 7. A cam 8 mounted upon the sprocket wheel 5 forming an integral part of the rotary valve 4 operates a pump plunger 10 controlled by a spring 9, which plunger sucks in

35 the fuel and forces it into the nozzle 7 by means of non-return valves 11 and 12. The pump chamber is sealed by a solid rotary valve 13. This rotary valve 13 is provided with an eccentric groove 14 by means of

40 which the pump chamber can be put in communication with the bypass 15 and thus with the fuel supply pipe 16. The regulation of the working volume of the pump is effected by means of the handle 17. It will be readily understood that instead of a piston pump

45 any other suitable pump may be employed, such as a gear wheel pump or the like.

50 My improved engine functions as follows: During the expansion stroke of the engine the rotary valve 4 is closed, i. e. the cylinder port is covered so that the fresh air coming

from the blower accumulates in the cylinder. Towards the lower dead center the pressure first escapes through the exhaust slots 18, then the valve slot 6 opens and the 50 fresh air accumulated by the blower scavenges the cylinder. Now the fuel pump becomes operative by the plunger being forced into the pump chamber by the cam and thus opening the non-return valve 12 and simultaneously closing the non-return valve 11 and ejecting the fuel through the nozzle 7. The quantity of the ejected fuel depends upon the position of the handle 17. If the eccentric groove provides an unobstructed 55 communication between the pump chamber and the fuel supply pipe 16, the entire quantity of fuel set in motion by the plunger is forced back into the supply pipe 16 because the resistance of the capillary nozzle 7 is 60 greater than the resistance of the bypass. The more this bypass is throttled by a corresponding adjustment of the valve 13 the more fuel issues from the nozzle 7. By an accurate adjustment of the pump valve 13 65 the actually supplied quantity of fuel can be at any time easily diminished to the desired value.

70 Various modifications and changes may be made without departing from the spirit 85 and the scope of the invention, and I desire, therefore, that only such limitations shall be placed thereon as are imposed by the prior art.

I claim as my invention:

1. In an internal combustion engine, in combination, a rotary tubular valve for controlling the scavenging and the charging air, a fuel injecting nozzle opening axially into said valve and a fuel supply pump adapted to operate in the cycle of said valve and to supply the fuel to the charge air in countercurrent.

2. In an internal combustion engine, in combination, a rotary tubular valve for controlling the scavenging and the charging air, a fuel injecting nozzle opening axially into said valve, a fuel supply pump, a cam on the face of said valve and adapted to operate said pump and to supply the fuel to the charge air in countercurrent.

3. In an internal combustion engine, in combination, a cylinder, a piston in said cylinder, a crank shaft, a connecting rod between said piston and said crank shaft, a tubular rotary valve located in the head of said cylinder, means for revolving said valve

- provided with a port, a fuel nozzle located axially in said valve, a cam on the outer face of said valve, a spring-controlled pump plunger adapted to be operated by said cam, 5 a pump chamber for said plunger, a fuel supply pipe opening into said chamber, a conduit connecting said chamber with said nozzle, and non-return valves in said pipe and said conduit.
- 10 4. In an internal combustion engine, in combination, a cylinder, a piston in said cylinder, a crank shaft, a connecting rod between said piston and said crank shaft, a tubular rotary valve located in the head of 15 said cylinder, means for revolving said valve provided with a port, a fuel nozzle lo- cated axially in said valve, a cam on the outer face of said valve, a spring-controlled pump plunger adapted to be operated by said cam, a pump chamber for said plunger, a 20 fuel supply pipe opening into said chamber, a conduit connecting said chamber with said nozzle, non-return valves in said pipe and said conduit, a rotary valve for sealing said pump chamber, a handle for rotating said valve, 25 an eccentric groove in said valve, and a bypass leading from the chamber of said valve into said fuel supply pipe and adapted to be controlled by said groove.
- 11 In testimony whereof I have affixed my 30 signature.

FRITZ DÜRR.
